UNITED STATES PATENT OFFICE.

BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPEWRITING MACHINE.

Application filed January 20, 1922. Serial No. 530,503.

To all whom it may concern:

Be it known that I, BURNHAM C. STICKNEY, a citizen of the United States, residing in Elizabeth, in the county of Union and State of New Jersey, have invented certain new and useful Improvements in Typewriting Machines, of which the following is a specification.

This invention relates to the type-actions and appurtenant devices of typewriting machines. Many of its features are of value in a variety of ways, and are illustrated as embodied in a machine for writing Arabic and related languages.

Nearly all of the letters of the Arabic alphabet are written each in one form for the beginning of a word, in a second form for the middle of a word, in a third form for the end of a word, and in a fourth form when standing alone. This makes it necessary to employ such a number of types in printing or typing in Arabic as to be practically prohibitive for typewriters of the Underwood and other front-strike type-bar machines, in which only from eighty to ninety-six types are provided.

To overcome this discrepancy, it has been proposed to vary the forms of the Arabic letters, so as to reduce the number of types required therefor, but this has not been found acceptable to general users. It has also been proposed to split some of the types, printing each of many characters with one silent key for part of the character (such key common to many characters), and another key for the main portion of the character; but this plan has not been found acceptable in practice. It has also been proposed to make selections from the various forms of many of the letters in the alphabet, in such a way as to require the use of only a few types.

One of the features of the present invention resides in adapting a front-strike type-bar machine of the Underwood type for use for typing in Arabic without resorting unduly, if at all, to any of the various expedients above recited. To this end there may be employed upon the forty-two to forty-eight type-bars of an Underwood typewriting machine (this being the number usually employed upon standard English writing machines of the front-strike type-bar class) a series of normally operative types, which preferably include the median forms of

Arabic letters; these types being the most frequently used, and printing without the use of any shift-key. There may be also provided a shift-key corresponding to the usual capital shift-key in the Underwood machine, which may bring into use another set of types upon the same type-bars, this set printing preferably the initial forms of the Arabic letters. In this way there is avoided the necessity of altering the forms of the characters, or of adopting to an objectionable extent, if at all, any of the other objectionable expedients above noted; and for the purpose of typing the final forms of the Arabic letters, there is provided an additional shift-key, which brings into use a third set of types upon the same system of type-bars; while for the isolated forms of the Arabic letters, there is provided upon the same type-bars a fourth set of characters, brought into use by a third shift-key. Said set of type-bars is also capable of accommodating various accent and other ancillary marks or characters characteristic of the Arabic language, including numerals, punctuation marks, etc.

The four forms of the same alphabetical letter are placed upon one type-bar in each case, so that the key for each four-type type-bar needs to bear only a single character, while the shift-keys may designate which of the three special forms of that type may be selected. In this way the Arabic language may be typed fully, in a correct and acceptable manner, substantially corresponding to that in which it is usually printed by the use of movable types.

In applying the invention to an Underwood machine, the usual type-bars are lengthened sufficiently to accommodate the added sets of types; and the bars or rails that are usually mounted at the upper front part of the framework are mounted in higher positions and more towards the front of the machine, to give clearance for the lengthened type-bars; the posts which carry said bars or rails being extended to support the bars in their new positions. The platen is made shiftable from normal to three positions by the use of three shift-keys. The platen stops are modified, and two new stops are made movable and put under the control of the two shift-keys, so that the platen may be positively arrested and maintained in each of its four typing positions. The de-

vices upon which the platen frame swings are modified so as to be capable of giving it triple the usual range of movement; and the same is true of the swinging shift-rail frame which shifts said platen frame; said shift-rail frame being operable by any of the three shift-keys. The ribbon-vibrator is connected to shift with the platen to each of its three abnormal case-shift positions, and to be vibrated to cover and uncover the printing point at the type strokes at each position of the platen.

The invention is not limited to the use of Arabic or other alphabet. Certain features may be used for other purposes, and the shifting mechanism is capable of modification for such purposes.

Other features and advantages will hereinafter appear.

In the accompanying drawings,

Figure 1 is a sectional side elevation taken for the most part centrally of the machine from front to rear, and showing the platen in its lowermost or normal position for typing medial letters.

Figure 2 is a diagram showing type-blocks with type-faces thereon, each block having four forms of the same letter. These forms are shown diagrammatically, but it will be understood that in making the actual types the forms are reversed.

Figure 3 is a sectional elevation of the machine taken in rear of the keyboard and forward of the platen.

Figure 4 is a diagram of a keyboard, showing the Arabic alphabet with only a single character on each key, said key serving throughout all of the four forms of its letter.

Figure 5 is a sectional elevation corresponding to a portion of Figure 1, but showing the platen shifted up one step to bring into use the initial types.

Figure 6 is a plan showing the universal bar frame and ribbon-vibrating devices.

Figure 7 is a view similar to Figure 5, but showing the platen shifted up to a third position for printing final characters.

Figure 8 is a view similar to Figure 7, but showing the platen shifted to its topmost position for typing isolated characters.

Type-keys 10 depress levers 11 having pins 12 to engage slots 13 formed in bell-crank 14, to swing type-bars 15 upwardly and rearwardly against a platen 16. The type-bars 15 are pivoted at 17 in an arc below the printing point, the arc being about in a vertical plane, as usual, and have slots 18 engaged by pins 19 in the bell-crank 14.

Upon the type-bars may be carried blocks 20, each having four types 21, 22, 23, 24, of which the lowermost one 21 prints when the platen is in normal position, any of the others being brought into use by appropriately shifting the platen up.

The invention is in the nature of an improvement on the standard Underwood typewriting machine, and makes provision for room for the additional types on the type-bars by raising and bringing forward the usual margin-gage rod 25 and front rail 26 at the front of the machine, these being supported upon upward and forward extensions 27 provided upon the front part of the usual framework 28 and carrying the usual front scale 29. The usual roll 30 runs upon the front rail 26, this roll being mounted in the front bar 31 of the platen carriage 32, which front bar clears the lengthened type-bars because it is elevated above the remainder of the carriage upon upward and forward extensions 33 provided at the front of said carriage and cast integral therewith; said bar 31 being, however, below the line of vision, so that the typing is visible as it is being written. Thus by simple changes and without objectionable cost the typing capacity of the Underwood machine is doubled, while the appearance of the machine is preserved.

The usual platen 16 is directly journaled upon a platen frame 34, shiftable upward by means of a swinging shift-rail 35, upon which runs a roll 36 pivoted to bracket 37 depending from the rods 38, 38^a forming part of the shift-frame 34, the latter having substantially the usual construction. The shift-frame 34 has at its ends gudgeons 39, which are engaged by arms 40 extending forward from a rock-shaft 41 pivoted in ears 42 formed upon the main carriage 32, substantially as usual in the Underwood machine. The shift-frame is also guided in its up-and-down movement by a pair of links 43, which are pivoted at 44 to the carriage and at 38^a to the shift-frame.

The platen occupies its lowermost position at Figure 1, and is shiftable upwardly thrice the distance usual in the Underwood machine. To effect this movement without causing the platen to swing unduly out of a vertical path, the relationship of the pivot points 41 and 39 is changed from the standard construction, by elevating the point 41, so that said points 39 and 41 will be about on a level with each other when the platen has moved half way through its extreme upward throw. For similar reasons the pivot points 38^a and 44 have a similar relation. The platen is rotated little or none at the case-shifting operations, and the front or printing line of the platen is caused to travel in an arc which nearly coincides with a vertical line, so that the printing efficiency of the types is not impaired, and no great deviation of the types from a straight row on the type-block is necessary; the type-faces on the block lying in approximately a single plane.

The shift-rail 35 is carried upon a pair of

side plates 45 and 60 extending forwardly from a rock-shaft 46, journaled in the side posts 47 of the machine. These side plates 45 and 60 are approximately of the usual construction, but this shift-rail frame normally stands in a more depressed position than usual, owing to the necessity of giving the shift-rail 35 triple the usual throw. The relationship of the parts 35 and 46 corresponds with that of the pivots 39 and 41, so that the shift-rail 35 moves up nearly in a vertical line.

The shifting of the shift-rail frame, comprising plates 45 and 60 and rock-shaft 46, may be effected by the use of three shift-keys, the first of which is marked 48 and is mounted upon a shift-lever 49, corresponding in shape with the type-key-levers 11, and having at its rear end an arm 50 to rock upon the rear edge 51 of the left-hand plate 45 of the shift-rail frame, this operation being substantially like that which is usual in the Underwood machine, see Figure 5.

The upward movement of the platen frame 34 is arrested by a stop 52, arranged upon the carriage in the path of a shoulder 53 provided upon the shift-frame, Figure 5; it being understood that there is a stop 52 at each end of the carriage frame, and a shoulder 53 at each end of the platen frame. The platen frame normally rests at 54 upon the side bars of the carriage frame 32; the platen frame having a bent-down ear 55, whose lower edge rests upon the carriage bar at each end of the carriage, as usual in the Underwood machine. The throw of the platen, therefore, is limited downwardly by the ear 55 resting upon the carriage side-bar, and upwardly by the shoulder 53 engaging the stop 52. This enables either of the two lower types on the type-bar to be printed. The stop 52 is loosely mounted, but there is provided upon the carriage a fixed guide 56 for the stop 52, so that the latter really serves as an interponent between the shoulder 53 and the fixed guide or stop 56, Figure 5, and hence accurate alignment of the upper and lower case type-impressions with one another is secured.

When it is desired to bring into use the third type on each type-bar, there is depressed a key 57 on a lever 58, preferably at the right-hand side of the machine, said lever having at its rear end an upstanding arm 59 to engage the right-hand side plate 60 (resembling 45) of the shift-rail frame. The shifting movement of the platen effected by the key 57 is the same as that effected by said key 48. It will be seen at Figure 7 that the platen is shifted above the Figure 5 position far enough for the third types 23 to print. The arm 59 may roll upon a flange 61 provided upon the plate

60 and flush with the rear edge of the latter. In order to remove the loose stop or interponent 52 from the path of the shoulder 53, there is provided upon the shift-key a cam 62, which acts upon a pin 63 provided upon a bell-crank 64, to swing the latter and pull down a link 65, which, at its upper end, connects to an arm 66, and thereby rocks a shaft 67 extending between the posts 27 on the framework and journaled therein, and having midway between its ends an arm 68 to lift a transversely-arranged horizontal bar 69 journaled at 70 upon arms 71 extending downwardly and rearwardly from the front bar 31 of the carriage. This cross-bar or shaft 69 has at its ends arms 72, pivotally connected at 73 with stops 52, to slide the latter from their normal positions at Figure 1 forwardly to positions at Figure 7, whereby stops 52 are removed from the path of the rising shoulders 53, and a second pair of stops 74 is brought into play, these stops 74 being formed as jogs on the stops 52, and the latter being guided on shoulder screws 75. The cam 62 may be provided with a dwell, so that the stop-plates 52 may remain motionless during the last part of the platen-shifting stroke of the key 57. Thus the platen is arrested in position for the third type to strike, and accurate alignment of these type-impressions with the others is secured, because the stops or parts 74 serve as interponents, being pushed by the shoulders 53 against the aforesaid fixed stops 56. Upon relieving the key 57 from pressure, the platen returns by gravity to its lowest position (the usual counter-balancing spring being not shown) and the remaining parts resume their normal positions, the stop-plates 52 being returned by springs 76, together with the stop-setting bar 69. The link 65 and connections may fall back to normal positions, aided by springs 76.

When it is desired to print the topmost types 24 on the bars, a key 77 may be depressed, Figure 8, said key being mounted upon a lever 78 at the left-hand side of the lever 58; and an arm 79 upon lever 78 may engage the plate 60 and swing the shift-rail frame up to the extreme position at Figure 8. The shifting of the stop-plates 52 is effected by a cam 80 upon said lever 78, which engages pin 63 to shift bell-crank 64, link 65, arm 66, rock-shaft 67, arm 68, stop-shifting bar 69 and arms 72, to withdraw the members 52 entirely from the paths of the shoulders 53, so that the latter engage directly the fixed parts or stops 56 upon the carriage, Figure 8. Said stops 56 therefore really serve as final stops for all three shifts of the platen frame, and hence the alignment of the type-impressions is reliable. Upon the release of the

key 77 from pressure, all the parts are the lowering of the shift-rail 35. At its returned to normal positions, Figure 1.

The ribbon-winding mechanism is not shown, but it may be substantially the same as in any Underwood machine, or of any usual or standard construction. A ribbon-guide 81 at the front of the platen may be of substantially the usual form, and is seen at normal position in Figure 1, with the ribbon 82 below the printing point. The mounting and operation of the ribbon-guide may be such as to accommodate the extra throw of the ribbon necessary to accommodate the two additional shifting positions of the platen. For this purpose the ribbon-guide may have side flanges 83 to embrace the fixed type-guide 84 in front of the platen, these side flanges 83 extending down far enough to permit the longest throw of the ribbon-guide without running up off from the type-guide. The ribbon-carrier 81 is also provided (for its lower end) with a fixed guide in the form of a vertical post 85, rising from a part 86 of the framework of the machine overlying the key-levers. The ribbon-guide has at its lower end an ear 87 perforated to fit upon the guide 85; this ear being formed upon the lower end of a downward rigid extension 88 of the ribbon-guide, which is thus given substantial length, and hence is kept under control without being made unduly heavy, and without the necessity of tight fitting of the parts.

35 The ribbon-guide is shifted up and down at the type strokes by means of an arm 89 projecting forwardly from a rock-shaft 90, and having at its end a slot 91 to engage a pin 92 fixed upon the ribbon-guide. Above this pin the guide extends forwardly at 93 and upwardly at 94 alongside of the rear guiding face of the type-bar segment 95. The rock-shaft 90 is capable of up-and-down case-shifting movements, since it extends horizontally between the plates 45, 60 of the shift-rail frame, and is pivoted thereto so as to shift therewith together with the ribbon-vibrator 81. From said rock-shaft 90 extends a short arm 96, which is connected by a link 97 to an ear 98 fixed upon the universal bar frame 99 of the ribbon-vibrating and carriage-feeding mechanism. The link is pivoted to said ear at 100, and the relationship of the pivot 100, the link 97, the arm 96, the pivot 90, and the arm 89, is such that as the platen shifts up to its different stations, the ribbon-guide 81 and the ribbon 82 shift accordingly, so that the printing line on the platen is properly covered by the ribbon at all shifts of the platen, at the strokes of the type-bars. The curved universal bar carried by the frame 99 is seen at 101 and is substantially of usual form. The sides of the universal bar frame 65 are bent downwardly at 102 to accommodate

70 rear end the universal bar is pivoted at 103 to the usual upright arms 104. At each type-stroke the universal bar 101 is pressed rearwardly, together with the frame 99 and 75 ear 98, thereby pulling on the link 97 and rocking the arm 96 and shaft 90, and hence lifting the arm 89 together with the ribbon-guide 88, 94, 81, so that the ribbon covers the printing point as the type strikes. 75

80 There are diagrammatically illustrated at Figure 2 examples of the type-blocks 20, in dotted lines, one type-block containing the types for the four forms of the Arabic letter "ha", and the other having the letter "num". It will be understood that other type-bars are used for other letters of the Arabic alphabet, one type-bar for each letter, each type-bar having all four forms of the same letter. In cases where a letter has less than four forms, the type-bar may have a corresponding number of letters thereon. For convenience, the types are shown at Figure 2 as having the same form as the type-impressions have upon the work-sheet, these forms being the reverse of what would actually appear upon the types. Since the platen 16 is normally in lowermost position, the bottom types 21 upon the type-blocks 90 print the medial characters of Arabic words, 95 so that a large proportion of the writing may be effected without holding down a shift-key. The second types 22 are for the initial forms of the alphabetical letters, these types being brought into play by depression of the left-hand shift-key 48, which has to shift the platen only one step, so that the work of shifting for the frequently used initial characters may be minimized. The 100 third types 23 upon the type-blocks are for the final forms of the characters, and there is used therefor the key 57, which shifts the platen two steps, as at Figure 7. The types 24 upon the type-blocks are for the isolated forms of the letters, and, as these are used 105 less than any of the other forms, the key 77 is used therefor, this being the shift-key which is the most laborious to depress, as it throws the platen the greatest distance, 110 Figure 8. 115

120 At Figure 4 is shown diagrammatically the keyboard of the machine, each alphabet key 10 having only one character 105 thereon. These characters for the most part represent medial letters, and are typed when the platen is in its lowermost or normal position. Any of the other three forms on any type may be brought into use by first depressing the appropriate shift-key 48, 57 125 or 77, so that only a single alphabetical character needs to appear on each of the alphabet keys; this being an important advantage over previous keyboards, in which each key bore two alphabetical characters, tending to confuse and retard the operation. 130

In some instances, as in the case of "alif", "dal", "dhal", "ra", "zai" and "waw", the alphabet does not contain final and medial forms. In these cases the keys for 5 these types need not print any alphabetical letters when the platen is in normal position, but only when the platen is shifted to appropriate positions.

Many of the keys are shown blank. These 10 may be from fourteen to eighteen in number, so that opportunity is afforded for from sixty to eighty accents, punctuation marks, figures and special marks, so as to practically meet all the needs for typewriting in 15 Arabic and other languages of which Arabic may be taken as the base.

Variations may be resorted to within the scope of the invention, and portions of the improvements may be used without others.

20 Having thus described my invention, I claim:

1. A front-strike type-bar typewriting machine comprising type-bars, each having four types thereon, a platen, and a platen-shifting mechanism including a set of three 25 shift-keys for shifting the platen in the same direction from its normal position to three different positions, and means, including shift-key-controlled stop devices, for stopping the platen in all four of said positions.

2. A front-strike type-bar typewriting machine comprising type-bars, each having four types thereon, a platen, and a platen-shifting mechanism including a set of three 35 shift-keys for shifting the platen in the same direction from its normal position to three different positions, and means, including shift-key-controlled stop devices comprising two fixed stops and two movable stops, for 40 stopping the platen in all four of said positions.

3. A front-strike type-bar typewriting machine comprising type-bars, each having four types thereon, a shiftable member, and 45 a case-shifting mechanism including a set of three shift-keys for shifting said member in the same direction from its normal position to three different positions, and means, including shift-key-controlled stop devices 50 comprising relatively fixed stops for limiting the extreme movements of the shiftable member and intermediate stops movable into and out of effective positions, for stopping the shiftable member in all four of said 55 positions.

4. A front-strike type-bar typewriting machine comprising type-bars, each having four types thereon, a platen, and a platen-shifting mechanism including a set of three 60 shift-keys for shifting the platen in the same direction from its normal position to three different positions, and means, including shift-key-controlled stop devices comprising two fixed stops and two movable stops connected to each other to move as a unit, for 65

stopping the platen in all four of said positions.

5. A front-strike type-bar typewriting machine comprising type-bars, each having four types thereon, a shiftable member, and 70 a case-shifting mechanism including a set of three shift-keys for shifting said member in the same direction from its normal position to three different positions, and means for stopping the platen in all four of said 75 positions, including shift-key-controlled stop devices having relatively fixed stops for limiting the extreme movements of the shiftable member and intermediate stops movable into and out of effective positions, said movable 80 stops connected to each other and movable as a unit.

6. A front-strike type-bar typewriting machine comprising type-bars, each having four types thereon, a shiftable member, and 85 a case-shifting mechanism including a set of three shift-keys for shifting said member in the same direction from its normal position to three different positions, and means for stopping the platen in all four of said 90 positions, including shift-key-controlled stop devices having relatively fixed stops for limiting the extreme movements of the shiftable member and intermediate stops movable into and out of effective positions, said movable 95 stops connected to each other and movable as a unit, and normally occupying a position between the fixed stops.

7. A front-strike type-bar typewriting machine comprising type-bars, each having four types thereon, a shiftable member, and a case-shifting mechanism including a set of three shift-keys, and also including shift-key-controlled stop devices including relatively fixed stops for limiting the extreme 100 movements of the shiftable member, and intermediate stops movable into and out of effective positions, said movable stops connected to each other and movable as a unit, and including one stop for arresting the platen or shiftable member at its shortest stroke, and another stop for limiting the next longest stroke of the platen or case-shift member, said intermediate stops being under the control of each of two shift-keys 105 which impart the longest throws to the shiftable member.

8. A front-strike type-bar typewriting machine comprising type-bars, each having four types thereon, a platen, and a platen-shifting mechanism including a set of three shift-keys, and also including shift-key-controlled stop mechanism, the latter including two fixed stops and two movable stops, said stop mechanism including stops adjacent to each end of the platen.

9. A typewriting machine provided with front-strike type-bars and a platen, said type-bars having each four types thereon, a letter-feeding carriage for said platen, keys 130

at the keyboard for effecting shifting of said platen from normal position to any one of three case-shifting positions, and movable-stop mechanism controlled by certain of the 5 shift-keys and including movable stops at the ends of the carriage.

10. A typewriting machine provided with front-strike type-bars and a platen, said type-bars having each four types thereon, a letter-feeding carriage for said platen, keys at the 10 keyboard for effecting shifting of said platen from normal position to any one of three case-shifting positions, movable-stop mechanism controlled by certain of the shift-keys 15 and including movable stops at the ends of the carriage, and means including a bar extending along the run of the carriage for maintaining a connection between shift-keys at the keyboard and the movable-stop 20 devices upon the carriage.

11. A typewriting machine comprising a platen carriage and front-strike type-bars, each extended to carry four types, the types and platen being relatively shiftable, and the 25 carriage comprising a frame which has a front bar portion which is elevated above the remainder of the carriage to clear the extended type-bars, said front bar being below the line of vision.

30. 12. A typewriting machine comprising a set of front-strike extended type-bars, each carrying four types, a carriage, a platen, a shiftable platen frame upon said carriage, pairs of arms connecting said platen frame to said carriage to guide the platen, and a stop mechanism, including stops on the carriage, for arresting the platen in four positions.

40. 13. A typewriting machine comprising a set of front-strike extended type-bars, each carrying four types, a carriage, a platen, a shiftable platen frame upon said carriage, a shift-rail frame mounted upon the framework of the machine to shift the platen frame to four case positions, pairs of arms connecting said platen frame to said carriage to guide the platen substantially vertically, and a stop mechanism, including stops on the carriage, for arresting the 45 platen in four positions.

50. 14. In a typewriting machine comprising front-strike extended type-bars carrying four types each, a platen shiftable to four case positions, a shift-rail frame mounted upon the framework of the machine to shift the platen, and three shift-keys, each capable of shifting the rail frame a different distance from the remaining shift-keys, while the latter remain stationary, one of said 55 shift-keys placed at one side of the keyboard, and the remaining shift-keys placed at the other side of the keyboard, arms being provided upon said shift-rail frame, and elbow levers being operated by said keys and engaging said arms.

15. In a typewriting machine comprising front-strike extended type-bars carrying four types each, a platen shiftable to four case positions, a shift-rail frame mounted upon the framework of the machine to shift the platen, and three shift-keys, each capable of shifting the rail frame a different distance from the remaining shift-keys, while the latter remain stationary, one of said shift-keys placed at one side of the keyboard, 70 and the remaining shift-keys placed at the other side of the keyboard, arms being provided upon said shift-rail frame, and elbow levers being operated by said keys and engaging said arms, one of said rail frame arms operable by two keys, and having a flange for engagement by one of the key levers.

16. In a typewriting machine comprising front-strike extended type-bars carrying four types each, a platen shiftable in the same direction from a normal to three other case positions, a shift-rail frame mounted upon the framework of the machine to shift the platen, three shift-keys, each capable of shifting the rail frame a different distance from the remaining shift-key, and movable intermediate stops controllable by two of said keys.

17. The combination of a carriage, a platen frame shiftable thereon, the carriage having fixed portions for limiting the extreme case-shifting movements of the platen frame, and movable stops for engaging the platen frame and for limiting the intermediate case-shifting movements thereof.

18. The combination of a carriage, a platen frame shiftable thereon, the carriage having fixed portions for engaging the platen frame and for limiting the extreme case-shifting movements thereof, and movable stops for limiting the intermediate case-shifting movements of the platen frame, said movable stops each comprising a plurality of shoulders for arresting the platen frame in a plurality of intermediate positions.

19. The combination of a carriage, a platen frame shiftable thereon, the carriage having fixed portions for engaging the platen frame and for limiting the extreme case-shifting movements thereof, movable stops for limiting the intermediate case-shifting movements of the platen frame, said movable stops each comprising a plurality of shoulders for arresting the platen frame in a plurality of intermediate positions, and means for shifting said movable stops to two different positions to bring different shoulders thereon into use.

20. The combination of a carriage, a platen frame shiftable thereon, the carriage having fixed portions for engaging the platen frame and for limiting the extreme case-shifting movements thereof, movable stops for limiting the intermediate case-shifting movements thereof, and means for shifting said movable stops to two different positions to bring different shoulders thereon into use.

iting the intermediate case-shifting movements of the platen frame, said movable stops each comprising a plurality of shoulders for arresting the platen frame in a 5 plurality of intermediate positions, and means for shifting said movable stops to two different positions to bring different shoulders thereon into use, said stop-shifting means including a rocking member connected to both of said movable stops.

21. The combination of a carriage, a platen frame shiftable thereon, the carriage having fixed portions for limiting the extreme case-shifting movements of the platen 15 frame, movable stops for limiting the intermediate case-shifting movements of the platen frame, said movable stops each comprising a plurality of shoulders for arresting the carriage in a plurality of intermediate positions, means for shifting said movable stops to two different positions to bring different shoulders thereon into use, said stop-shifting means including a rocking member connected to both of said movable stops, and means upon the framework of the machine to engage and operate said rocking member at all portions of the carriage travel.

22. The combination of a carriage, a platen frame shiftable thereon, the carriage having fixed portions for limiting the extreme case-shifting movements of the platen frame, movable stops for limiting the intermediate case-shifting movements of the platen 35 frame, said movable stops each comprising a plurality of shoulders for arresting the carriage in a plurality of intermediate positions, means for shifting said movable stops to two different positions to bring different shoulders thereon into use, said stop-shifting means including a rocking member connected to both of said movable stops, means upon the framework of the machine to engage and operate said rocking member at all portions of the carriage travel, and a plurality of keys for operating said rocking member and simultaneously shifting the platen.

23. The combination of a carriage, a platen frame shiftable thereon, the carriage having fixed portions for limiting the extreme case-shifting movements of the platen frame, movable stops for limiting the intermediate case-shifting movements of the platen 55 frame, said movable stops each comprising a plurality of shoulders for arresting the carriage in a plurality of intermediate positions, means for shifting said movable stops to two different positions to bring different shoulders thereon into use, said stop-shifting means including a rocking member connected to both of said movable stops, a transverse rock-shaft journaled upon the framework and having between its ends an arm to engage said rocking member

on the carriage, and keys to operate said rock-shaft.

24. The combination of a carriage, a platen frame shiftable thereon, the carriage having fixed portions for limiting the extreme case-shifting movements of the platen frame, movable stops for limiting the intermediate case-shifting movements of the platen frame, said movable stops each comprising a plurality of shoulders for arresting the carriage in a plurality of intermediate positions, means for shifting said movable stops to two different positions to bring different shoulders thereon into use, said stop-shifting means including a rocking member connected to both of said movable stops, a transverse rock-shaft journaled upon the framework and having between its ends an arm to engage said rocking member on the carriage, and keys to operate said rock-shaft, said rock-shaft having at its ends arms pivotally connected to the movable stop members.

25. In a typewriting machine comprising a carriage, front-strike extended type-bars carrying four types each, a platen frame shiftable to four case positions, a shift-rail frame mounted upon the framework of the machine to shift the platen frame, three shift-keys, each capable of shifting the rail frame a different distance from the remaining shift-keys, the carriage having fixed portions for limiting the extreme case-shifting movements of the platen frame, and movable stops for limiting the intermediate case-shifting movements of the platen frame, said stops operable by said keys.

26. In a typewriting machine comprising a carriage, front-strike extended type-bars carrying four types each, a platen frame shiftable to four case positions, a shift-rail frame mounted upon the framework of the machine to shift the platen frame, three shift-keys, each capable of shifting the rail frame a different distance from the remaining shift-keys, the carriage having fixed portions for limiting the extreme case-shifting movements of the platen frame, and movable stops for limiting the intermediate case-shifting movements of the platen frame, said stops operable by said keys and each comprising a plurality of shoulders for arresting the carriage in a plurality of intermediate positions.

27. A typewriting machine comprising a ribbon-vibrator, a platen, a platen carriage, and front-strike extended type-bars, each carrying four types, means for case-shifting the platen from normal position to three abnormal positions, means for shifting the ribbon-vibrator or guide with the platen, and means for causing the ribbon-vibrator to cover and uncover the printing point at the type-strokes in all positions to which the ribbon-vibrator shifts with the platen,

3
said typewriting machine having a type-guiding post, and said ribbon-vibrator having guide-flanges to engage said post to guide the ribbon-vibrator between its extreme positions, a downward extension upon said ribbon-guide and descending below said post, and means to guide said downward extension.

28. In a front-strike type-bar typewriting machine, the combination with two relatively shiftable elements, one of which is a platen and the other of which is a system of type-bars, each having four types thereon, of a mechanism to effect relative case-shifting between the elements to bring any selected set of types into use, said shifting mechanism including three shift-keys and also including two stops controllable by two of said shift-keys.

29. In a front-strike type-bar typewriting machine, the combination with two relatively shiftable elements, one of which is a platen and the other of which is a system of type-bars, each having four types thereon, of a mechanism to effect relative case-shifting between the elements to bring any selected set of types into use, said shifting mechanism including shift-keys and also including a plurality of shift-key-controlled stops and constructed so that at the operation of different shift-keys the element controlled thereby shifts one or more complete steps while the other element remains stationary.

30. In a front-strike type-bar typewriting machine, the combination with two relatively shiftable elements, one of which is a platen and the other of which is a system of type-bars, each having four types thereon, of a mechanism to effect relative case-shifting between the elements to bring any selected set of types into use, said shifting mechanism including three shift-keys and also including two stops controllable by two of said shift-keys, means controlled by one of said shift-keys for shifting the shiftable element one step, means controlled by another of said shift-keys for shifting the shiftable element two steps, and means controlled by another of said keys for shifting the shiftable element three steps.

31. In a front-strike type-bar typewriting machine, the combination with two relatively shiftable elements, one of which is a platen

and the other of which is a system of type-bars, each having four types thereon, of a mechanism to effect relative case-shifting between the elements to bring any selected set of types into use, one of said elements constructed to occupy four shift positions, and said shifting mechanism including fixed stops to determine the extreme positions of said shiftable element and movable stops to determine its intermediate positions.

32. In a typewriting machine, the combination with two relatively shiftable elements, one of which is a system of type-bars carrying four sets of types, of three shift-keys for effecting relative shifting movements of said elements, and a set of shift-stops including a stop shiftable into and out of effective position and connected to one of said keys to be controlled thereby.

33. In a typewriting machine, the combination with two relatively shiftable companion elements, one of which is a platen and the other of which is a system of type-bars, each type-bar carrying four types, of shift-keys, one capable of effecting an element shift of one full step while the companion shiftable element remains stationary, and another key capable of effecting an element shift of two full steps while the companion element remains stationary, and stop mechanism to control the relative positions of said elements for all four sets of types.

34. In a typewriting machine, the combination with two relatively shiftable companion elements, one of which is a platen and the other of which is a system of type-bars, each type-bar carrying four types, of shift-keys, one capable of effecting an element shift of one full step while the companion shiftable element remains stationary, and another key capable of effecting an element shift of two full steps while the companion element remains stationary, and stop mechanism to control the relative positions of said elements for all four sets of types, the stop mechanism including means for positively arresting a shiftable element or bringing it to a dead stop after the shifting operation.

BURNHAM C. STICKNEY.
